CLAIM

The ornamental design for a shoe, as shown and described.

DESCRIPTION

FIG. 1 is a bottom front perspective view of a shoe showing my new design;

FIG. 2 is a bottom view thereof; and,

FIG. 3 is a bottom rear perspective view thereof.

The broken line showing of the unshaded area in the rearfoot of the shoe forms no part thereof. The broken lines depicting the remainder of the shoe form no part of the claimed design.
